UNITED STATES PATENT OFFICE.

JULIUS RITTER, JR., AND MARTIN RASMUSSEN, OF RACINE, WISCONSIN, ASSIGNEES
TO HARTMANN TRUNK COMPANY, OF RACINE, WISCONSIN, A CORPORATION OF
WISCONSIN.

TRUNK LOCK.

Application filed November 6, 1925. Serial No. 67,312.

This invention relates to improvements in trunk locks, more particularly adapted for locking trunk sections together.

- It is one of the objects of the present invention to provide a trunk lock in which one of the securing members locking the trunk sections together is controlled by the movement of the other securing member to and from the locking position.
- 10 A further object of the invention is to provide a trunk lock in which the movement of the controlling lock towards its locking position will automatically draw the trunk sections together, and a movement of the controlling lock towards open position will automatically initially swing the sections apart.

20 A further object of the invention is to provide a trunk lock in which the principal portions of the securing members are mounted on the outer side of the trunk.

25 A further object of the invention is to provide a trunk lock in which the movable latching member is rigidly connected to the reciprocal bar forming the connection between the two securing members.

30 A further object of the invention is to provide a trunk lock which is of simple construction is strong and durable and is well adapted for the purpose described.

35 With the above and other objects in view the invention consists of the improved trunk lock and its parts and combinations as set forth in the claims and all equivalents thereof.

40 In the accompanying drawing in which the same reference characters indicate the same parts in all of the views:

Fig. 1 is an inner side view of the upper portion of a wardrobe trunk provided with the upper portion of the improved lock;

45 Fig. 2 is a similar view of the lower portion of a trunk provided with the lower portion of the latch;

Fig. 3 is a transverse sectional detail view on a larger scale taken on line 3—3 of Fig. 1; and

50 Fig. 4 is a transverse sectional detail view taken on line 4—4 of Fig. 2.

Referring to the drawing the numeral 8 indicates one section and 9 the other section of a wardrobe trunk which are hinged

together and are adapted to swing horizontally to open or closed position. The two sections are locked together at two points 55 by the improved securing means which comprises an upper keyed lock 10 and a lower automatic latch 11 controlled by the movement of the upper lock 10. The upper or keyed lock 10 is mounted on the trunk section 9 and is formed with a hinged hasp portion 12 arranged to swing into locking engagement with an escutcheon plate 13 mounted on the other trunk section 8. Said lock swings on the pivot pin 10'. The lock portion 14 of the hinged hasp is controlled by a key 15. The hinged portion 12 carries an arm 16 which extends into the trunk section 9 and its inner angular end portion 16' is formed with an eye 17 for pivoted connection with a two part link member 18 slidably positioned within the trunk section 9. The two portions of the link member are connected together by a pivot pin 19 to permit independent movement of the two parts 65 when the hasp member is moved to open position. The inner end of the two part arm is pivotally connected to the upper end of a bell crank lever 20 by a pivot pin 21. Said pin 21 is of sufficient length as to permit lateral 70 play of the link member 18 so that the opposite end of the link can swing in an arc when moved by the inner end of the arm 16. The bell crank lever 20 is fulcrumed on a plate 22 which is mounted on the trunk 75 part 9. A connecting bar 23 pivotally connected at its upper end to the lower arm 20' of the bell crank lever 20 extends downwardly therefrom and is rigidly connected at its lower end to a latch plate member 24 forming part of the lower latch 11. Said latch plate member 24 at its forward end is bent to form a bolt receiving rectangular opening or eye 25 for receiving the hooked end of the fixed bolt 26 mounted on the other trunk section 8. The rear end portion of the lock plate member 24 is formed with an angularly extending slot 27 through which a guide pin 28 extends. Said pin 28 projects outwardly from a plate 29 mounted on the trunk section 9. The open rectangular portion 25 of the plate 24 formed by bending a portion of said plate is covered on its outer side by an escutcheon plate 30. The hook

bolt 26 is rigidly connected to the trunk section 8 and projects outwardly from the edge thereof to partly enter the space formed by the other trunk section 9, and the escutcheon plate 30 when the two sections are swung together. The numeral 31 indicates an angular reinforcing strip for the edge of the section 9. The angular slot of the lock plate 24 extends upwardly and inwardly from the edge portion of the trunk section so that when the connecting bar 23 is pushed downwardly by swinging the hasp lock to open position, the lock plate will be moved downwardly and outwardly to a position to aline with the end hook portion of the fixed bolt member 26. When in said position the closing of the upper hasp lock will cause the lower latch plate to move upwardly and inwardly and engage the hook 20 of the bolt member and draw the two trunk sections together while locking the lower portion of said sections together. In opening the upper hasp lock, the lock plate as before stated will be pushed downwardly and outwardly and the two trunk sections will be initially moved to open position as the inner wall of the rectangular opening of the locking plate will engage and push outwardly on the hook portion of the fixed bolt. 30 In operation, the two trunk sections are swung together, which will approximately aline the opening 25 of the lock plate member 24 with the hooked end of the fixed bolt 26. The hasp or keyed lock member 14 is then swung inwardly towards the escutcheon plate 13, and in swinging the arm 16, which is mounted on the hasp and extends into the trunk section 9 and is connected to the bell crank lever 20 by the part link 18, the upper arm of the bell crank lever 20 is swung inwardly, away from the hasp, and the lower arm 20' of said lever upwardly. The link 23 which is pivotally connected to the bell crank arm 20' will be pulled upwardly by said upward swing so that the opening of the lock plate 24 will engage the hooked end of the fixed bolt 26, as shown in Figs. 1 and 2. In moving upwardly to locked position, the latch plate member 24 will be moved inwardly by the pin and diagonal slot engagement with the plate 29 and clamping 50 ly draw the two trunk sections together. As soon as the two trunk sections are in closed position, as shown in Figs. 1 and 2, the hasp member is pushed into the socket of the escutcheon plate and the bolt portions of the hasp member will snap into locking engagement with the escutcheon plate. To unlock, a key is inserted in the hasp lock to unlock 60 the bolts, and as the hasp member is swung outwardly the link will be moved downwardly to disengage the latch member 24 from the hook 26, as clearly shown in the drawings.

65 From the foregoing description, it will be

seen that the trunk lock is of very simple construction and is well adapted for the purpose described.

What we claim as our invention is:

1. In a trunk lock, a pair of spaced securing mechanisms, one of which is provided with a pivoted hasp portion, a slidable member moved by the hasp portion, a bell crank lever connected to the slidable member, the other of the securing mechanisms having a hook member and a latch member for receiving the hook member, and a bar member pivotally connected to the bell crank lever and rigidly connected to the latch member for moving said latch member into locking engagement with the hook member. 70

2. In a trunk lock, a pair of spaced securing mechanisms, one of which is provided with a pivoted hasp portion, a slidable member moved by the hasp portion, a bell crank lever having one of the arms connected to the slidable member, the other of the securing mechanisms having a fixed hook member and a movable latch member for receiving the hook member, and a bar member pivotally connected to the bell crank lever and rigidly connected to the latch member for moving said locking member into latch engagement with the hook member. 80

90

when the hasp portion of the other securing mechanism is swung to closed position. 95

3. In a trunk lock, a pair of spaced securing mechanisms, one of which is provided with a pivoted hasp portion having an inwardly extending arm, a slidable member pivotally connected to and moved by the arm, a bell crank lever having one of its arms connected to the slidable member, the other of the securing mechanisms having a fixed hook member and a movable latch member for receiving the hook member, and a bar member pivotally connected at its upper end to the other arm of the bell crank lever and rigidly connected at its lower end to the latch member for moving said locking member into locking engagement with the hook member when the hasp portion of the other securing mechanism is swung to closed position. 100

105

110

4. In a trunk lock for a trunk having two sections, a pair of spaced securing mechanisms, one of which is provided with a pivotal hasp portion having an inwardly extending arm, a two part slidable member pivotally connected to and moved by the arm, a bell crank lever having one of its arms connected to the slidable member, the other of the securing mechanisms having a fixed hook member for one trunk section and a latch member for the other trunk section, said latch member having an eyed portion which is entered by the hook member when the trunk sections are swung to closed position, means for causing the latch member to move in an angular direction, and 115

120

125

130

a bar member pivotally connected at its upper end to the other arm of the bell crank lever and rigidly connected at its lower end to the latch member for moving said latch member.

5. In a trunk lock for a trunk having two sections, a pair of spaced securing mechanisms, one of which is provided with a pivotal hasp portion having an inwardly extending 10 arm, a slideable arm member pivotally connected to and moved by the arm, a bell crank lever having one of its arms connected to the slideable member, the other of the securing mechanisms having a fixed hook member for 15 one trunk section and a latch member for the other trunk section, said latch member

having an angularly extending slot and an eyed portion which is entered by the hook member when the trunk sections are swung to closed position, a pin mounted on the adjacent trunk section and extending through the angularly extending slot for guiding the latch member in an angular direction, and a bar pivotally connected at its upper end to the other arm of the bell crank lever and rigidly connected at its lower end to the latch member for moving said latch member.

In testimony whereof, we affix our signatures.

JULIUS RITTER, JR.
MARTIN RASMUSSEN.
